UNITED STATES PATENT OFFICE.

HANS PAULIN ENEVALD PETERSEN, OF FOND DU LAC, WISCONSIN.

MOTOR-STARTER.

1,250,647.

Specification of Letters Patent. Patented Dec. 18, 1917.

Application filed May 18, 1917. Serial No. 169,396.

To all whom it may concern:

Be it known that I, HANS P. E. PETERSEN, a subject of the King of Norway, and a resident of Fond du Lac, in the county of Fond du Lac and State of Wisconsin, have invented a new and Improved Motor-Starte, of which the following is a full, clear, and exact description.

This invention relates to motors and particularly to an improved device for properly starting a kerosene motor, and has for an object the provision of an improved construction whereby the kerosene may be properly vaporized on the first compression so as to immediately explode.

Another object in view is to provide an improved construction of cylinder head with a heating chamber and means for independently heating part of the heating chamber so as to produce a proper gasifying of the oil at the time and immediately previous to the time of ignition.

In the accompanying drawing:—

Figure 1 is a longitudinal vertical section through a cylinder head disclosing an embodiment of the invention.

Fig. 2 is a side view of a heating core embodying certain features of the invention.

Fig. 3 is a top plan view of a heating sleeve or drum.

In explosive engines using a light oil, as for instance, gasolene, an explosion may be secured quickly by reason of the rapid gasifying of the gasolene when properly carbureted and drawn in and compressed. However, when a heavier oil, as for instance, kerosene is used in the explosive engine it is necessary to heat the cylinder and certain of the parts in some manner in order to produce a proper explosion. Heretofore it has been customary to use gasolene or other light oil for starting kerosene motors and running the motors until the parts have become sufficiently heated to allow the use of kerosene.

According to the present invention means have been provided for heating certain parts of the cylinder head whereby no gasolene or other light fuel is necessary and yet the engine may be started instantly.

Referring to the accompanying drawing by numerals 1 indicates a cylinder head which in general outline may be of any suitable kind and connected with any suitable structure or cylinder, head 1 being provided with an inlet and an exhaust of some kind. The special construction of head 1 includes a

projection 2 having a bore 3 and an offset threaded portion 4 for receiving the cap 5 which is threaded into the offset portion 4. The cap 5 is provided with an opening 6 for receiving a spark plug 7 formed with an annular extension 8 having a beveled overhanging portion 9 for fitting against the beveled upper edge of the heating sleeve 10.

The heating sleeve or drum 10 fits into an annular recess or offset portion from bore 3, as shown in Fig. 1, so as to rest upon the annular shoulder 11 and to be pressed tightly into position by the annular extension 8. The sleeve or drum 10 is preferably made from some easily heated material which will quickly transmit the heat, as for instance, brass. In forming this drum an annular or peripheral part 12 is provided connected by transverse partitions 13 and 14 extending entirely across the drum and merging into each other at the center, as shown in Fig. 3, whereby four passageways 15, 16, 17 and 18 are provided.

Each partition is provided with an offset or shouldered portion 19 and apertures 20 extending from the shoulder diagonally through the partition, as shown in Fig. 1, whereby during the compression stroke the fumes of the oil will pass up through the passageways 15 to 18 inclusive, and will strike against these shoulders where it is broken up more or less and some caused to pass through the apertures 20 for producing a further breaking up. The drum 10 is to be heated so that any of the particles striking the same will be gasified thoroughly by the heat absorbed so that the gasified fuel compressed in the space 21 near the spark plug 7 will provide ample gas for producing an explosion.

In order to heat the drum or sleeve 10 before the engine is started so as to cause an immediate explosion as soon as the engine is turned over, heating cores 22 and 23 are provided, said cores extending through apertures 24 and 25 in the extension 2, the inner part of the cores having a curved shaped face 26, as shown in Fig. 2, so as to fit snugly against the drum 10 and transmit heat thereto. These cores may be of brass or other suitable material. Each core is provided with a beveled portion 27 which coacts with the beveled portion of the respective nuts 28 and 29 whereby the cores are clamped tightly in position and an air-tight connection produced. By thus producing an air-tight con-

nection at this point and producing an air-tight connection by the annular extension 8 insures against any loss of gas at any time. The outer part of the cores 22 and 23 have 5 connected thereto in any suitable manner heating coils 30 and 31 which are to receive current from any suitable source (not shown) and which may be turned off or on at any time.

10 Usually when it is desired to start the engine both coils 30 and 31 are supplied with current and heat is transmitted therethrough from cores 22 and 23 and from said cores to the drum 10. From drum 10 the 15 surrounding parts of the extension 2 and cap 5 will be heated to a certain extent. This heat is maintained as long as desired, preferably a comparatively short time, and then the engine is turned over, whereupon the kerosene 20 vapor is drawn in and compressed in the extension 2, and by reason of the heat therein, and especially in drum 10, it will become gasified and thereby easily ignited. It is of course understood that not all of the gas is 25 compressed into the extension 2, but sufficient for the purpose desired, as said extension and associated parts may be of any desired size in comparison with the cylinder. After the engine explodes and starts to running it is preferable to turn off one of the 30 heating coils as a less heat will be sufficient, though it is desirable to have at least one coil continually in use for some time or until the regular explosions have heated the cylinder and cylinder head sufficiently to insure 35 a proper gasifying of the carburetor kerosene. It will be understood that the construction is such that any motor operated with crude oil or any oil or fuel can easily 40 be started.

What I claim is:

1. In a motor structure of the character described, the combination with an engine provided with a cylinder head formed with 45 a tubular extension, said tubular extension being provided at the upper end with means for receiving a sparking device, a drum arranged intermediate the ends of said tubular extension, said drum being formed with 50 a partition acting as means for breaking up the gases and vaporous matter passing into the tubular extension during the compression stroke, and means arranged exteriorly of the extension for heating said drum 55 whereby the gases and vaporous matter will be converted into a combustible mixture by the time it reaches the sparking device.
2. In a starting device for kerosene engines, the combination with an engine formed 60 with a cylinder head having a tubular extension, of a drum arranged in said tubular extension, said drum being formed with openings therethrough, a core contacting with

said drum and extending to a point exteriorly of the extension, and heating elements arranged on said core for heating the same whereby heat is transmitted to said drum, converting the fuel compressed in said head into an easily combustible mixture. 65

3. In a motor starter of the character described, the combination with a motor provided with a head having a tubular extension, of a heating sleeve arranged in said extension, a cap overlapping said heating sleeve and holding the same tightly in position, and heating elements extending from the exterior of the extension into contact with the sleeve for heating the same. 70

4. The combination with a kerosene motor, of means for starting the motor, said means including a heating sleeve arranged in the head of the cylinder of the motor, heating cores contacting with said sleeve and extending to the exterior, and heating elements connected to said cores for heating 75 the cores. 80

5. The combination with a kerosene motor, of heating means for heating the fuel drawn into the cylinders thereof, said heating means comprising a heating sleeve provided with a peripheral portion and a pair of partitioning members whereby the sleeve is divided into a plurality of openings, each of said partitioning members being offset and formed with apertures therethrough for 85 breaking up the explosive mixture, and heat transmitting means extending from the exterior of the head of the cylinder of the engine into contact with said sleeve. 90

6. The combination with a kerosene motor 100 provided with a cylinder having a head with a tubular extension, of a heating sleeve arranged in said extension and divided into compartments, a plurality of core members fitting against said sleeve and extending to 105 the exterior of the extension, a clamping nut for each of said core members, for clamping the core members tightly against the sleeve and also providing a substantially gas-tight joint, and an electrical heating element arranged on the outer end of each of said cores. 110

7. In a heating element for explosive engines, the combination with a cylinder provided with a tubular extension, of a heating drum arranged in said extension formed with a beveled upper end, means for supplying heat to said heating element, and a cap arranged on said extension formed with an annular extension having an overhanging 115 portion fitting against the beveled portion of the sleeve whereby the sleeve is held firmly in position and a substantially gas-tight joint produced. 120
